US0D1013924S

(12) **United States Design Patent** (10) Patent No.: **US D1,013,924 S**
(45) Date of Patent: ** Feb. 6, 2024

(54) **SPOTLIGHT**

(71) Applicant: **Zumtobel Lighting GmbH**, Lemgo (DE)

(72) Inventors: **Harald Gruendl**, Vienna (AT); **Gernot Bohmann**, Vienna (AT); **Martin Bergmann**, Vienna (AT)

(73) Assignee: **ZUMTOBEL LIGHTING GMBH**, Lemgo (DE)

(**) Term: **15 Years**

(21) Appl. No.: **35/512,709**

(22) Filed: **Sep. 1, 2021**

(80) **Hague Agreement Data**

Int. Filing Date: **Sep. 1, 2021**

Int. Reg. No.: **DM/216522**

Int. Reg. Date: **Sep. 1, 2021**

Int. Reg. Pub. Date: **Oct. 8, 2021**

(51) LOC (14) Cl. **26-05**

(52) U.S. Cl.

USPC **D26/63**

(58) **Field of Classification Search**
